UNITED STATES PATENT OFFICE.

LOUIS A. CASGRAIN, OF WINCHESTER, MASSACHUSETTS, ASSIGNOR TO
UNITED SHOE MACHINERY COMPANY, OF BOSTON, MASSACHUSETTS.

MACHINE FOR INSERTING METALLIC FASTENINGS.

SPECIFICATION forming part of Letters Patent No. 669,024, dated February 26, 1901.

Original application filed October 26, 1899, Serial No. 734,828. Divided and this application filed January 23, 1901. Serial No. 44,375. (No model.)

To all whom it may concern:

Be it known that I, LOUIS A. CASGRAIN, a citizen of the United States, residing at Winchester, county of Middlesex, State of Massachusetts, have invented an Improvement in Machines for Inserting Metallic Fastenings, of which the following description, in connection with the accompanying drawings, is a specification, like characters on the drawings representing like parts.

This invention relates to a machine for forming and inserting fastenings having shanks or bodies and heads provided with depending points, constituting hook-shaped heads.

The present application is a division from another application, Serial No. 734,828, filed by me October 26, 1899. In the machine described and claimed in said application, Serial No. 734,828, the length of the shanks of the fastenings was varied automatically according to variations in thickness of the stock; but in the machine of this application the character or length of the shank of the fastening is determined by the workman through manually-operated devices.

Figure 1 represents in side elevation, with the driving-pulley removed, a portion of the machine represented in application Serial No. 734,828, filed October 26, 1899, with my present improvements added. Fig. 1^a is a detail showing the means for moving the regulator. Fig. 2, on a smaller scale, represents the lower end of the column, showing the treadles. Fig. 3 is a plan view of the parts shown in Fig. 2. Fig. 4 is a detail in plan view of the wire-feeding means and actuating devices therefor. Fig. 5 is a sectional detail in the line α , Fig. 4, of the wire-feeding means. Fig. 6 shows the two manually-controlled levers for actuating the regulator, said levers being substituted for other levers fully shown and described in said application; and Fig. 7 represents, on an enlarged scale, a fastening such as will be made on the machine described.

Referring to the drawings, the column A, standing on the floor and sustaining the head A², in which is mounted the main shaft C, the stud D', the starting lever or device C¹⁸, hav-

ing as its fulcrum the rock-shaft C⁹ and provided at one end with a stud C¹⁷ and having the extremity of its connected arm C¹⁶ bevelled, said starting-lever being moved in one direction to start the main shaft of the machine and moved in the opposite direction by a spring C¹⁴, the wire-feeding means, (represented as wheels c' c²), deriving their movement from spring-pressed pawls c¹⁰ c¹², mounted on a toothed pawl-carrier c¹³, actuated by a slide-bar e, connected with a lever E, said pawls engaging a ratchet-toothed wheel c⁹, fast on the shaft c⁸, carrying the feed-wheel c', and the regulator e¹², having shields e⁷ and e⁸ for controlling the time at which said pawls in the stroke of the pawl-carrier, which is uniform, shall engage the ratchet-wheel, and thereby insure a definite amount of movement of the wire to be formed into a fastening, are common to the machine shown in said application. In said application, however, the extent of feeding movement imparted to the wire, and consequently the length of the fastenings, is controlled automatically by variations in the thickness of the stock, while in the machine of my present application I have provided novel devices where-through the length of the fastenings is determined by manually-operated devices under the control of the workman.

In the machine herein shown the column A has at its lower or floor end a pivot D⁶, which sustains two treadles D⁵ D^{5X}, and each treadle has a suitable arm or projection with which is connected one of two rods D⁴ D^{4X}. The rod D⁴ is extended upwardly and has clamped upon it a block D², having a stud which enters a hole in one arm 53 of a lever o², having an upwardly-projecting arm 61 and a depending arm 52. The rod D^{4X} is provided with a like block having a stud which enters a hole in an arm 51 of a lever o', having an upwardly-extending arm 60 and a depending arm 50. These two levers o' and o² have their hubs bored and are both pivoted on the stud D'.

Herein the stub C¹⁷, carried by the starting-lever, is longer than in the machine of said application, and said stud is arranged to be

acted upon by either of the arms 60 61 of the levers o' o^2 , and either of said levers may be turned by the workman through one of the treadles D^5 or D^{5X} to start the main shaft C 5 of the machine through means fully described in said application.

Herein the regulator e^{12} instead of being moved by a single rod, as provided for in said application, is moved by either of two rods, 10 as 54 55. The rod 54 is moved by the arm 52 of the lever o^2 , while the rod 55 may be moved by the arm 50 of the lever o' . Each of these rods has a stop, as 56 or 57, and by adjusting these stops more or less of the movement of 15 the levers o' or o^2 may be made effective in moving the rod connected with it, and consequently the regulator e^{12} , carrying the shields e^7 and e^8 . As fully explained in said application, changing the position of the shields 20 with relation to the ratchet-wheel varies the time of engagement of the pawls c^{10} and c^{12} in their forward stroke with said ratchet-wheel, and thereby regulates the operation 25 of the wire-feeding mechanism and causes the production of fastenings differing in length.

The stops 56 and 57 are preferably held frictionally in position upon the rods 54 and 30 55 by suitable set-screws, as 58, which bear against suitable washers 59, contacting with the rod.

It will now be seen that in the machine embodying my present invention the workman will by simply depressing one of the treadles both start the machine and operate the mechanism which controls the length of fastening 35 to be produced by the machine. It will also be understood that by the single operation of depressing one treadle the workman both starts the machine and causes the production of a fastening of a predetermined length, while by 40 the single operation of depressing the other treadle the workman both starts the machine and causes the production of a fastening of another predetermined length.

45 In the machine herein partially illustrated the wire will be formed into fastenings by means fully described in said application, and the formed fastenings will be driven by a driver carried by a driver-bar b^3 , actuated as provided for in said application, and said means need not therefore be herein more fully described, as they form no part of the invention claimed herein.

Some manufacturers may desire to insert 55 the peculiar fastenings one of which is illustrated in Fig. 7, which will be produced by the machine herein partially illustrated and fully described in said application, so that the shanks of the fastenings and the points 60 depending from their heads may stand cross-wise of the sole, and at this time the workman standing in front of the machine will present the shoe to the usual nose b , so as to receive from it the fastenings in the direction 65 stated and will start the machine by putting his foot on one or the other of the treadles

$D^5 D^{5X}$, according to the length of the fastening desired. Other manufacturers, however, desire that the shanks and the points depending from the heads shall stand in a line substantially parallel with the edge of the sole, and at such time the workman for convenience of handling the shoe may prefer to stand at the right-hand side of the machine, and to permit this the treadles D^5 and D^{5X} have 70 been provided with supplemental footpieces $p^2 p^3$.

With the levers having the extra footpieces $p^2 p^3$ the workman may operate the machine with equal convenience whether standing in 80 front of the machine or at the right-hand side thereof.

When the lever o' is actuated by its treadle, the rod 55 moves the regulator to put its shield in such position about the toothed surface of the ratchet-wheel c^9 of the wire-feeding mechanism that the spring-pressed pawls c^{10} and c^{12} when the pawl-carrier c^{13} is moved, as stated, will meet the teeth of said ratchet-wheel and move the wire-feeding mechanism 90 for a distance to make, for instance, the longest fastening, and such movement of the rod 55 in the direction of the arrow near it, Fig. 1^a, will move the stop 56 of the rod 54 toward the end of the arm 52 of the lever o^2 . So 95 long as the operator retains his foot on the treadle D^{5X} , controlling the movement of the lever o' , the longest fastenings will be made and driven; but on arriving at the shank, where a shorter fastening should be inserted, 100 the operator will remove his foot from the treadle D^{5X} and put it on the treadle D^5 , causing the arm 52 of the lever o^2 to be moved in the direction of the arrow y near it in Figs. 1 and 1^a, it pushing in front of it the stop 56, 105 with which it is in contact. The rod 54 will thus be moved to put the shields in such position with relation to the ratchet-teeth of the wire-feeding mechanism that when the pawls again go forward they will be prevented by the shields from engaging said ratchet-teeth until a later point in their stroke, so that a shorter fastening will be produced. During this operation the rod 55 will be moved opposite the arrow next to it, thus 110 moving the stop 57 toward the arm 50 in readiness to be acted upon when a longer fastening is again required.

I provide the regulator with a friction device f^3 , which acts against a fixed part of the 115 machine, and by turning a screw f^4 (see Fig. 5) I may cause said device to exert any desired amount of friction, so that the regulator will not be moved accidentally and can be moved only when actuated positively by the 120 rods 54 or 55.

In order to control positively the positions of the shields in making the different lengths of fastenings, I have provided means whereby the movements of both treadles in each 130 direction are limited. The lever D^5 has been provided with a suitable pin or projection r

and the lever D^5X with a projection r' , said projections each entering suitable notches r^2 in a depending guide or bar r^3 , said notches being of lengths corresponding to the movements desired for the treadles. The under sides of the notches limit or determine the extent of downward movement of each treadle under the action of the foot of the workman and the upper ends of said notches determine the extent of upward movement of each treadle under the action of a spring D^7 , common to said application. I have so arranged the pins r and r' and the notches r^2 that the footpiece of each treadle, when it is depressed to its low position, is at a considerable distance from the floor, so that a full movement of the treadle is assured even in case there should be some obstruction below the footpiece.

I have shown these mechanisms as being adapted to cause the presentation to the machine of different lengths of fastenings, and I believe I am the first to use separate actuating mechanisms arranged for the starting and stopping of the machine and also for causing the insertion of fastenings of different characters or lengths, whether the fastenings be formed consecutively from continuous wire or whether they be formed from different wires or strips or whether the fastenings be presented to the machine already made, and I desire to claim, broadly, therefore, the embodiment in a machine of this class of separate actuating mechanisms each adapted to start and stop the machine and also to control the presentation of a fastening to be inserted by the machine in the stock. I also believe that I am the first to embody in a machine for inserting metallic fastenings formed from continuous wire an actuating mechanism adapted both for starting and stopping the machine and for controlling the action of the wire-feeding mechanism to determine the length of the fastening to be formed from said wire.

Having described my invention, what I claim as new, and desire to secure by Letters Patent, is—

1. A machine for inserting metallic fastenings of different lengths comprising wire-feeding mechanism, an actuating mechanism for starting the machine, and intermediate mechanism operated thereby for controlling the feeding of the wire for a fastening of the desired length.

2. A machine for inserting metallic fastenings comprising independent actuating mechanisms, each adapted for starting and stopping the machine, and also for controlling the presentation of a fastening to be driven by the machine.

3. A machine for inserting metallic fastenings formed from continuous wire comprising independent actuating mechanisms each adapted for starting and stopping the machine, and also for causing the feeding of the

wire for different lengths, whereby fastenings of different lengths may be formed and driven by the machine.

4. A machine for inserting metallic fastenings formed from continuous wire comprising independent actuating mechanisms each adapted for starting and stopping the machine, and also for regulating the feeding of the wire, and means to adjust said mechanisms whereby either may be actuated to cause the production of a fastening of the desired length.

5. A machine for inserting metallic fastenings comprising a plurality of treadle-operated actuating mechanisms for starting and stopping the machine, wire-feeding means and connections between said wire-feeding means and said actuating mechanisms wherethrough the feeding of the wire may be controlled by either of said actuating mechanisms.

6. A machine for inserting metallic fastenings formed from continuous wire comprising means for feeding the wire, and actuating mechanism adapted for starting and stopping the machine, and also for controlling the feeding of the wire and so determining the length of the fastening to be formed from said wire and driven by the machine.

7. In a machine for forming metallic fastenings, wire-feeding means, a plurality of treadles, connections between said treadles and wire-feeding means, and stops to determine the extent of movement of each treadle when depressed, each treadle insuring the feeding of a definite quantity of wire for the production of a longer or a shorter fastening.

8. A machine for forming metallic fastenings comprising wire-feeding mechanism, a pawl-carrier having a pawl to operate said wire-feeding mechanism, means to move said pawl-carrier for a uniform distance at each operation of the machine, a regulator to govern the operation of the pawl, a plurality of manually-controlled levers, and means actuated thereby and in operative connection with said regulator to position it and thereby determine the effective stroke of the pawl-carrier and the quantity of wire fed by the wire-feeding mechanism.

9. A wire-feeding mechanism comprising a ratchet-wheel and feed-wheels, a pawl-carrier having a pawl to engage said ratchet-wheel, a regulator having a shield adapted to be interposed between said pawl and ratchet-wheel to control the length of the effective stroke of said pawl, two rods connected with said regulator and provided with adjustable stops, and two manually-controlled levers either of which may be moved at the will of the workman to meet one of said stops and position the regulator to insure the feeding of the wire for one or another defined distance according to the length of fastening which it is desired to produce.

10. In a wire-feeding mechanism, a shaft provided with a feed-wheel and a ratchet-

wheel, a pawl-carrier having a pawl to engage said ratchet-wheel, a regulator having a shield, independent actuating means each adapted to move said regulator positively for a greater or less distance, and a friction device to maintain said regulator where left by its actuating means.

11. A machine for inserting metallic fastenings of different lengths comprising means for driving the fastenings and for guiding them

while they are being driven, and independent treadles for controlling the presentation of each length of fastening.

In testimony whereof I have signed my name to this specification in the presence of 15 two subscribing witnesses.

LOUIS A. CASGRAIN.
